UNITED STATES PATENT OFFICE

2,648,170

CORE CLEANER

Ernie Byron Esters, Highland Park, Mich.

Application January 22, 1951, Serial No. 207,208

9 Claims. (Cl. 51—3)

1

This invention comprises novel and useful improvements in core cleaning devices and more particularly pertains to a device for abrading the rough projections from the core.

An important object of this invention is to provide a device for cleaning the rough projections on each of the faces of the core; reduce the core to proper dimensions to thereby produce a smoother and more uniform core.

Another object of this invention is to provide a device which will simultaneously remove the projections on the faces and edges of the core while removing the projections in the openings formed in the core.

A further object of this invention is to provide a device for cleaning cores, in accordance with the foregoing objects, which device will automatically stop after the cycle of cleaning operations on each core has been completed.

An important feature of this invention resides in the provision of a core support, a reamer support mounted for movement relative to said core support, rotatable reamers carried by the reamer support for movement therewith towards and away from the core carried by the core support, with means for driving the reamers and moving the reamer support, and a mechanism for cyclically connecting and disconnecting the reamer support moving means from the driving means.

Another feature of this invention resides in the provision of a core cleaner, in accordance with the foregoing feature, with abrading plates carried by the reamer support for movement therewith into and out of engagement with the edge of a core carried by the core support to remove the rough projections from the edges of the core.

A further feature of this invention resides in the provision of a core cleaner, in accordance with the foregoing features, with a cover for the core support, and abrading bars carried by the cover, together with a mechanism reciprocating the abrading bars in response to movement of the reamer support, to remove rough projections from the face of the core.

Yet another feature of this invention resides in the provision of a core cleaner, in accordance with the foregoing features, with a clutch mechanism for selectively establishing a driving connection between a prime mover and the reamer support moving means, and a mechanism responsive to the closing of the cover for establishing driving connection between the members of the clutch mechanism, together with a mechanism responsive to the completion of the cycle of operation of the core cleaner for selectively disconnecting the clutch mechanism.

2

These, together with various ancillary objects and features are attained by this device, a preferred embodiment of which has been illustrated by way of example only in the accompanying drawings, wherein:

Figure 1 is a vertical sectional view, taken on the plane 1—1 of Figure 2;

Figure 2 is a top plan view of the core cleaner;

Figure 3 is a transverse vertical sectional view taken on the plane 3—3 of Figure 1;

Figure 4 is a transverse vertical sectional view taken on the plane 4—4 of Figure 1;

Figure 5 is a horizontal sectional view taken on the plane 5—5 of Figure 1;

Figure 6 is a horizontal sectional view taken on the plane 6—6 of Figure 1;

Figure 7 is a fragmentary sectional view of the clutch mechanism, taken on the plane 7—7 of Figure 6;

Figure 8 is a fragmentary transverse sectional view of the clutch mechanism, taken on the plane 8—8 of Figure 7;

Figure 9 is a diagrammatic view of the control system for the core cleaner; and

Figure 10 is a perspective elevational view of one type of core which the core cleaner is adapted to cleanse.

Reference is now made more specifically to the accompanying drawings wherein the core cleaner, denoted generally by the numeral 10, is illus-

trated, and which core cleaner includes a reamer driving mechanism 12, a reamer moving mechanism 14, an abrading mechanism 16 actuated in response to the reamer moving mechanism for cleaning the face of the core, and an abrading assembly 18 carried by the reamer support for movement therewith, into and out of engagement with the edges of the core to remove the rough projections therefrom.

The core cleaner 10 includes a frame having angle iron standards 20, which standards are secured together at their upper ends by angle iron side rails 22 and end rails 24, and at their lower ends by the flanged motor mounting plate 26.

A core supporting plate 28 is secured to the standards 20, intermediate their ends, and carries a plurality of upwardly extending core support posts 30 which are secured to the plate 28, as by fasteners 32. Each of the posts 30 has an extension 34 threadedly attached thereto, the heads 36 on the extension being formed so as to be receivable in depressions which are molded in the core. Obviously, the plate 28 may be provided with a plurality of apertures to permit the adjustable positioning of the posts 30 to correspond to the recesses in the core being worked

upon so as to support and center the core and, alternatively, if the core does not have depressions therein, it will be appreciated that the posts may be utilized to merely support the core.

A reamer support plate 38 is provided with openings 40 therein for guidably receiving the posts 30, angle iron end bars 42 being secured to the standards 20, below the end rails 24, to limit downward movement of the reamer support plate. Guide rails 44 are secured between the end rails 24 and the end bars 42 and are guidably received in notches 46 in the reamer support plate 38 to guide vertical reciprocatory movement of the latter. A plurality of flanged journals 48 are adjustably secured to the reamer support plate 38, as by fasteners 50 which extend through slots 52 in the plate 38, each of which journals rotatably receives a reamer spindle 54. A suitable reamer 56 is carried by the upper end of each spindle 54, and a bevel gear 58 is non-rotatably secured to the lower end of each spindle. The bevel gears 58 are in mesh engagement with complementary bevel gears 60 disposed on shafts 62, the latter being rotatably journaled in brackets 64 and 66, carried by the undersurface of the reamer mounting plate 38. A plate 68 connects the lower ends of the adjacent brackets 66, and provides a journal for the shaft 70 having the pinion 72 thereon, which pinion is adapted to drivingly engage the bevel gears 74 on the registering ends of the shafts 62. Although a suitable gear drive for the reamers has been described, it is to be understood that a belt or chain drive could be substituted without departing from the spirit of the invention.

In order to drive the pinion 72 carried by the shaft 70, there is provided an electric motor 76 which is secured by fasteners 78 to the motor mounting plate 26. The motor pulley 80 is connected by means of a belt 82 to a pulley 84 mounted on the main drive shaft 86. As is best shown in Figures 1 and 3, the shaft 86 is rotatably carried by journals 88 on the transverse angle iron braces 90 on the standards 20. A bevel gear 92 is non-rotatably disposed on the shaft 86 in meshing engagement with the bevel gear 94 on the vertically disposed reamer drive shaft 96, the shaft 96 being journaled in the bracket 98 carried by the side bars 100. The shaft 96 is provided with an internally splined socket 102 which receives the complementarily splined end 104 of the shaft 70, to thereby provide a longitudinally extensible coupling for the shafts.

The reamer moving mechanism 14 includes a cam shaft 106 rotatably disposed in journals 108 on cross members 110, and cam members 112 carried by the cam shaft.

Cam followers 114 are secured to the reamer mounting plate 38 and reciprocably extend through sleeves 116 on the core support plate 28, into engagement with the cam members 112. Thus, as the shaft 106 is rotated the reamer support plate 38 is vertically reciprocated whereby the reamers will be moved into and out of the bores in the core 118.

A clutch mechanism 120 is disposed on the cam shaft 106 and includes a first clutch member 122 rotatably mounted on the shaft 106 and having a pulley 124 secured thereto. A collar 126 is fixedly secured to the shaft 106 and engages the first clutch member to limit axial movement thereof, and a belt 128 is disposed about the pulley 124 and the pulley 130 on the main drive shaft 86, to drivingly connect the clutch mechanism to the motor 76. A second

clutch member 132 is splined to the shaft 106, as at 134 for sliding, but non-rotating movement thereon, and a compression spring 136 is disposed in the counterbore 138 in the second clutch member, which spring otherwise engages the cap member 140 which is fixed to the shaft 106, to thereby yieldingly urge the second clutch member into engagement with the first clutch member. As is shown in Figure 7, a collar 142 is carried by the cap to guide the spring and second clutch member as the latter is shifted axially on the shaft 106. A brace bracket 144 is secured to a mounting rail 146, to support the cam shaft intermediate its ends.

In order to move the clutch members into and out of engagement, the second clutch member 132 is provided with a peripheral cam surface 148 which is so constructed as to shift the second cam member axially on the shaft in opposition to the spring 136, when the vertically reciprocable, and laterally inflexible cam follower 150 engages the cam surface. As is best shown in Figures 1 and 9, the follower 150 is slidably and non-rotatably received in an internally splined sleeve 152 carried by the core support plate 28, and is provided with rack teeth 154 which mesh with a spur gear 156. The spur gear 156 is non-rotatably mounted on the stub shaft 158, which is journaled in bearing plates 160 and an arm 162 is fixedly secured to the stub shaft. The arm 162 is normally biased in a clockwise direction, as viewed in Figures 1 and 9, by a spring 164, whereby the follower 150 is normally urged into its cam engaging position. A solenoid 166 having a reciprocable plunger 168 actuated thereby, is provided to selectively move the follower 150 out of cam engaging position, the plunger being suitably pivoted to the arm 162. Thus, when the follower 150 is moved out of engagement with the cam surface 148, the clutch members will be moved into driving engagement by the spring 136, whereby the cam members 112 will be rotated by the motor 76, to reciprocate the reamer mounting plate 38. Conversely, when the follower 150 is disposed in engagement with the cam surface, the second clutch member is moved axially on the cam shaft 106 out of engagement with the first clutch member, as the second clutch member rotates.

The abrading mechanism 16 includes a cover 170 which is hingedly attached, as at 172, to one of the side rails 22, and a handle 174, to facilitate opening and closing of the cover. As is best shown in Figure 2, the cover is provided with a plurality of openings 176 for the reception of the projecting bosses 178 on the core 118. Obviously, the spacing of the openings will be regulated by the positioning of the bosses on the particular core and, if no bosses are utilized, the abrading bars, to be described hereinafter, may be mounted on the undersurface of the cover to smooth the face of the core. The abrading bars 180, 182 and 184, shown in the accompanying drawing, have abrading blocks 186 thereon, each of which blocks overlies one of the openings 176. An actuator arm 188 is pivotally attached, intermediate its ends as at 190, to the cover 170, and has one end pivotally connected by the pin 192 to the bar 180. An actuator link 194 is terminally pivoted as at 196 and 198 to the bars 180 and 182, and pivotally attached by the pin 200 to the cover. A second link 202 is pivoted by pin 204 to the cover, and terminally pivoted as at 206 and 208 to the links 180 and 184. It will thus be noted that as the actuator arm 188 is pivoted

about the pivot point 190, the bars 180, 182 and 184 will be moved longitudinally. Obviously, by varying the relative position of the pivots, the amount of movement may be regulated. Further, since the bars will tend to move in arcs about the pivot points of the links which are attached thereto, it will be appreciated that a loose pivotal connection between the links and bars must be provided to permit movement of the bars and links without binding. The bars 182 and 184 may be suitably guided in any desired manner, if desired to constrain movement of the bars to a predetermined path, and for this purpose the bar 184 may be provided with an elongated slot 210 which slidably receives a pivot pin 212 which is slidably disposed in a slot 214 in the actuator arm. Obviously, the slot 214 may be dimensioned so as to constrain, within prescribed limits, the movement of the bar 180 transverse its longitudinal axis.

A bell crank 216 is vertically pivotally mounted on the bracket 218 carried by the side rail 22, and has one arm thereof connected by link 220 to the reamer support plate 38, the other arm being received in the yoke 222 on the end of the actuator arm 188, whereby the bell crank will be vertically pivoted as the reamer plate is vertically oscillated, to thereby reciprocate the abrading bars through the intermediary of the actuator arm 188.

The abrading assembly 18 includes a plurality of Z-shaped brackets 224, one leg of each of which is secured to the reamer support plate 38, as by fasteners 226, the other leg of which brackets vertically pivotally support the abrading members 228. A spring 230 is interposed between the abrading members and the Z-shaped bracket to which they are attached to yieldingly urge the members into core engaging position. As is thought apparent, the size and shape of the abrading members, and their relative positioning on the reamer support plate will be dependent upon the shape of the core and the complexity of the form of the edges.

It is contemplated that the control of the engagement of the clutch members be regulated in response to the closing of the cover 170, and for this purpose there is provided a switch 232 which is electrically connected in series with the solenoid 166, and which switch is closed in response to closing of the cover 170 and yieldingly biased open, in any desired manner, when the cover is opened. Additionally, there is provided a cam operated switch 234 which is electrically connected in series with the switch 232 and the source of power (not shown). The switch 234 is constructed so as to remain in either open or closed position, dependent on the manner in which it is set. A cam 236 is carried by the cam shaft 106, and a follower rod 238 rides on the cam 236 to selectively move the switch 234 to its open position when the lobe on the cam 236 elevates the rod.

The motor 16 is connected to the source of power and the master switch 240, by conductors 242 and 244.

In operation, the switch 234 is first manually closed, prior to closing of the cover 170, so that when the cover is closed, the switch 232 will also be closed, thereby energizing the solenoid to retract the follower 150. It may be noted, however, that the switches 232 and 234 may be consolidated if there is provided a finger on the cover which will releasably engage the composite switch to move it into its closed position when the cover is closed, and which finger will release the switch

to permit the same to be opened, and remain open, by means of the follower rod 238 when the latter is vertically oscillated.

When the follower 150 is retracted, and the clutch members 122 and 132 moved into driving engagement, the shaft 106, and cam members 112 thereon will be rotated to vertically oscillate the reamer support plate 38 and the reamers carried thereby, into and out of the bores in the core 118. In this regard, it is to be noted that the reamers are being rotated, while being vertically oscillated, by means of the extensible coupling between the shafts 96 and 70, which drives the reamer drive shaft 62. As the reamer support plate is vertically oscillated, the abrading members 228 will engage the edges of the core 118 on the posts 30, to smooth the edges, and the abrading bars 180, 182 and 184 will be moved longitudinally to cause the blocks 186 to smooth the bosses 118, by means of the bell crank 216 which is pivoted in response to vertical oscillation of the reamer support plate, in a manner previously described.

The cam 236 is so shaped to cause the switch 234 to be opened a predetermined time before the reamers have been retracted from the bores in the core, and the abrading members moved out of engagement with the edges of the core, so that the follower 150 will be biased by the spring 164 into cam surface engaging position. Obviously, the cam surface 148, and the cam 236 must be so arranged that the clutch members will be disconnected after the reamers have been moved out of the bores in the core.

Having described the invention, what is claimed as new is:

1. A core cleaning machine comprising a supporting structure including a core support, a reamer support mounted on said supporting structure for movement relative to said core support towards and away from a core carried by the latter, a reamer rotatably mounted on said reamer support for movement about an axis parallel to the direction of movement of the reamer support, means connected to the reamer for rotating the same, means connected to the reamer support for moving the same, drive means connected to said reamer rotating means and said reamer support moving means, and means selectively connecting said reamer support moving means with said driving means for cyclically driving said reamer support moving means, abrading means mounted for movement transverse the direction of movement of said reamer support means for removing projections on a core carried by said core supporting means, and means responsive to movement of said reamer support means for moving said abrading means.

2. A core cleaning machine comprising a supporting structure including a core support, a reamer support mounted on said supporting structure for movement relative to said core support towards and away from a core carried by the latter, a reamer rotatably mounted on said reamer support for movement about an axis parallel to the direction of movement of the reamer support, means connected to the reamer for rotating the same, means connected to the reamer support for moving the same, drive means connected to said reamer rotating means and said reamer support moving means, and means selectively connecting said reamer support moving means with said driving means for cyclically driving said reamer support moving means, abrading means mounted for movement trans-

verse the direction of movement of said reamer support means for removing projections on a core carried by said core supporting means, and means responsive to movement of said reamer support means for moving said abrading means, a second abrading means carried by said reamer support means for movement therewith into and out of engagement with the edge of a core positioned on said core support means.

3. A core cleaning machine comprising a supporting structure including a core support, a reamer support mounted on said supporting structure for movement relative to said core support towards and away from a core carried by the latter, a reamer rotatably mounted on said reamer support for movement about an axis parallel to the direction of movement of the reamer support, means connected to the reamer for rotating the same, means connected to the reamer support for moving the same, drive means connected to said reamer rotating means and said reamer support moving means, a cover for said core support carried by said supporting structure, linkage movable by the closing of said cover for drivingly connecting said reamer support moving means to said driving means, means operatively connected to said reamer support moving means for cyclically disconnecting said drive means from said reamer support moving means, means carried by said cover for abrading the face of core carried by said core support, and means responsive to movement of said reamer support means for moving said abrading means.

4. A core cleaning machine comprising a supporting structure including a core support, a reamer support mounted on said supporting structure for movement relative to said core support towards and away from a core carried by the latter, a reamer rotatably mounted on said reamer support for movement about an axis parallel to the direction of movement of the reamer support, means connected to the reamer for rotating the same, means connected to the reamer support for moving the same, drive means connected to said reamer rotating means and said reamer support moving means, a cover for said core support carried by said supporting structure, linkage movable by the closing of said cover for drivingly connecting said reamer support moving means to said driving means, means operatively connected to said reamer support moving means for cyclically disconnecting said drive means from said reamer support moving means, abrading means carried by said reamer support means for movement therewith into and out of engagement with the edge of the core carried by said core support.

5. A core cleaning machine comprising a supporting structure including a core support, a reamer support mounted on said supporting structure for movement relative to said core support towards and away from a core carried by the latter, a reamer rotatably mounted on said reamer support for movement about an axis parallel to the direction of movement of the reamer support, means connected to the reamer for rotating the same, means connected to the reamer support for moving the same, drive means connected to said reamer rotating means and said reamer support moving means, a cover for said core support carried by said supporting structure, linkage movable by the closing of said cover for drivingly connecting said reamer support moving means to said driving means, means operatively connected to said reamer support moving means

for cyclically disconnecting said drive means from said reamer support moving means, means carried by said cover for abrading the face of core carried by said core support, and linkage connected to and actuated by movement of said reamer support means for moving said abrading means, a second abrading means carried by said reamer support means for movement therewith into and out of engagement with the edge of a core carried by said core support means.

6. A core cleaning machine comprising a supporting structure including a core support, a reamer support mounted on said supporting structure for movement relative to said core support towards and away from a core carried by the latter, a reamer rotatably mounted on said reamer support for movement about an axis parallel to the direction of movement of the reamer support, means connected to the reamer for rotating the same, means connected to the reamer support for moving the same, drive means connected to said reamer rotating means and said reamer support moving means, clutch means including first and second relatively movable members, said drive means being operatively connected to said first member, cam means carried by one of said members, a retractable follower engaging with said cam means for selectively moving said clutch members out of driving engagement with each other, said reamer support moving means being operatively connected to said second clutch member, a cover for said core support carried by said supporting structure, a solenoid operatively connected to said follower, and means responsive to closing of said cover for energizing said solenoid to retract said follower and establish a driving connection between said clutch members.

7. A core cleaning machine comprising a supporting structure including a core support, a reamer support mounted on said supporting structure for movement relative to said core support towards and away from a core carried by the latter, a reamer rotatably mounted on said reamer support for movement about an axis parallel to the direction of movement of the reamer support, means connected to the reamer for rotating the same, means connected to the reamer support for moving the same, drive means connected to said reamer rotating means and said reamer support moving means, clutch means including first and second relatively movable members, said drive means being operatively connected to said first member, cam means carried by one of said members, a retractable follower engaging with said cam means for selectively moving said clutch members out of driving engagement with each other, said reamer support moving means being operatively connected to said second clutch member, a movable cover for said core support carried by said supporting structure, a solenoid operatively connected to said follower, and means engageable with and responsive to closing of said cover for energizing said solenoid to retract said follower and establish a driving connection between said clutch members, a second cam means operatively connected to said second clutch member for selectively deenergizing said solenoid.

8. A core cleaning machine comprising a supporting structure including a core support, a reamer support mounted on said supporting structure for movement relative to said core support towards and away from a core carried by the latter, a reamer rotatably mounted on said reamer support for movement about an axis parallel to

the direction of movement of the reamer support, means connected to the reamer for rotating the same, means connected to the reamer support for moving the same, drive means connected to said reamer rotating means and said reamer support moving means, a movable cover for said core support carried by said supporting structure, means engageable with and responsive to the closing of said cover for drivingly connecting said reamer support moving means to said driving means, abrading means reciprocably mounted on said cover, a bell crank carried by said supporting structure, means operatively connecting said bell crank to abrading means for reciprocatory movement in response to oscillation of said bell 15 crank, and means operatively connecting said bell crank to said reamer support whereby said bell crank is oscillated in response to movement of said reamer support.

9. The combination of claim 8 wherein said 20 means connecting said bell crank to said abrading means includes an arm pivotally attached to said cover and connected to said abrading means,

and a yoke on the end of said arm engageable with said bell crank.
